UNITED STATES PATENT OFFICE.

JOHN BATLEY, OF ORANGE, NEW JERSEY.

IMPROVEMENT IN CHILDREN'S CRIBS.

Specification forming part of Letters Patent No. **132,745**, dated November 5, 1872.

To all whom it may concern:

Be it known that I, JOHN BATLEY, of Orange, county of Essex, State of New Jersey, have invented certain Improvements in Children's Cribs, of which the following is a specification:

The object of my invention is to construct and manufacture cribs for children which are given a lateral motion by being rocked, which is more comfortable and salubrious than a swinging or longitudinal motion.

In order to describe my invention more fully, I will refer to the accompanying drawing forming part of this specification.

Figure I is a side view of a child's crib embodying my invention. Fig. II is an end view, representing the hanging of the crib by aid of the two hangers. Fig. III is a cut sectional view through line *x x*, Fig. I.

Similar letters of reference indicate corresponding parts.

A is a frame resting on four legs, *a a*. To the side pieces *b b* of the frame A is fastened the cross-piece B, the top of which receives two curves, *c c*—these curves to correspond with the circle which the crib describes when being rocked. C C are two stands or standards, fastened to the center of the end pieces

d d of the frame A, which serve as supports for the crib D. To the top of these standards C C are pivoted either the hanger E, as represented in Fig. III, or the cross-piece F, fastened as represented in Fig. II. In Fig. III the single hanger E is also pivoted to the bottom end piece *g* of the crib D. In Fig. II the two hangers G G are pivoted to the cross-piece F, and also to the bottom end piece *f* of the crib D. Between the bottom side pieces *e e* of the crib D is placed a cross-piece, H, to which the guides *i i* are fastened. These guides, having rollers *j j* which roll on the two curves *c c*, serve to give the crib a steady lateral motion, which is in all respects preferable to any known or hitherto-used method of rocking children.

Having thus fully described my invention, I desire to claim—

The hangers E G G, the standards C C, the cross-pieces F B H, the curves *c c*, the guides *i i*, and the rollers *j j*, in combination with the frame A and crib D, substantially as and for the purpose hereinbefore set forth.

JOHN BATLEY.
